Primary Examiner — Derrick Holland*Assistant Examiner* — Lauren Calve*(74) Attorney, Agent, or Firm* — QuickPatents; Kevin Prince(57) **CLAIM**

We claim the ornamental design for a hanger, as shown and described.

DESCRIPTION

FIG. 1 is a perspective view of a hanger, showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines shown in FIG. 1 represent unclaimed subject matter and form no part of the claimed design.
